UNITED STATES PATENT OFFICE

ARTHUR HERMAN ADAMS, OF LA GRANGE, ILLINOIS, ASSIGNOR TO WESTERN ELECTRIC COMPANY, INCORPORATED, OF NEW YORK, N. Y., A CORPORATION OF NEW YORK

METHOD OF TREATING OBJECTS

Application filed November 19, 1927. Serial No. 234,361.

This invention relates to a method of treating objects, and more particularly to a method of applying coating material to objects.

5 The object of this invention is to provide an improved method of treating objects in an expeditious and economical manner to provide a smooth, uniform coating.

It is believed that a complete understanding of the improved method will be procured from a description of one embodiment of an apparatus by means of which the method may be practiced to uniformly and smoothly coat small objects with a metallic 15 material.

In accordance with the aforementioned object one embodiment of an apparatus by means of which the method may be practiced comprises a freely rotatable basket containing loosely arranged objects to be coated, which is designed to be immersed in a bath of molten tin, zinc, alloy, wax, pitch, or other coating material. The bath, which may be tin, is contained in a rotatable receptacle provided with an enlarged portion.

20 When the receptacle is rotated, motion is also imparted to the perforated basket through the bath of molten tin, and when a certain speed is attained the major part of 25 the tin is gradually thrown outwardly, due to the action of centrifugal force as speed is acquired and collects in the enlarged portion of the receptacle, leaving the perforated basket entirely free of the bath of tin. During 30 this stage of the operation the bath of molten tin gradually recedes from the objects in the basket, removing as it recedes all excess tin by the combined effect of the 35 surface tension of the bath of tin and of centrifugal and gravitational forces, thereby resulting in a smooth and uniform coating.

The effect is the same as though a basket of objects was withdrawn from a bath of tin in a much greater gravitational field 40 than the earth affords.

Other objects and advantages of this invention will more fully appear from the following detail description taken in connection with the accompanying drawings which illustrate one embodiment of an apparatus by

means of which the method may be practiced, in which

Fig. 1 is a fragmentary plan view of an apparatus embodying the features of this invention;

55

Fig. 2 is a vertical section, partly in elevation, taken on the line 2—2 of Fig. 1, and

Fig. 3 is a fragmentary detail section through the vertical axis of the basket which holds the objects.

60

Referring now to the drawing in detail wherein like reference numerals indicate similar parts, and particularly to Fig. 2, a circular base 10 rotatably supports by means of suitable antifriction bearings a circular receptacle 11. Attached to a lower reduced bearing portion of the receptacle 11 is a worm gear 12 which meshes with a worm 13 which may be driven from a suitable source of power (not shown). The receptacle 11 is provided with an enlarged portion 14 at its upper end, the purpose of which will become apparent as this description progresses, the portion 14 having an axial opening 15 at its top surface.

75

Coaxially arranged with and rigidly supported above the receptacle 11 is a non-rotatable shaft 18 which is adapted to be reciprocated in a vertical direction by any suitable means (not shown), for instance a hydraulic cylinder. Rotatably mounted upon the lower end of the shaft 18 by suitable anti-friction bearings is a sleeve 19, a head 20 of the shaft holding the sleeve thereon. The sleeve 19 is provided in the present instance with three outwardly and downwardly extending arms or spiders 21.

80

Suspended from the free ends of the spiders 21 is a circular basket 23 formed of sheet metal having its vertical and lower walls perforated, the whole being strengthened by a plurality of metal bands 24, the upper ends of which extend above the top edge of the basket and above a normal immersion level 25 of the molten tin or other coating material. The free ends of the spiders 21 are attached to the upper ends of the bands 24 by suitable readily releasable means. The sleeve 19 is of such a length that taken with the three spiders 21, the basket 23 is

85

90

95

maintained sufficiently rigid upon the shaft 18 in the operation of the apparatus that no appreciable lateral movement of the basket within the receptacle 11 occurs. The receptacle 11 is provided with a plurality of circularly and uniformly arranged ribs 26 extending from its inner peripheral wall toward the axis thereof and spaced from the peripheral surface of the basket 23 sufficiently to not interfere with its free rotation. In addition to one purpose of the ribs 26 which will be described hereinafter in the description of operation of the apparatus, they also serve as a means to steady the basket 23 during its rotation and facilitate the guiding thereof through the opening 15 of the receptacle, and into the ring guard 33 when it is being withdrawn from the receptacle.

20 Removably attached at its lower end to the basket 23 within an opening formed axially in the lower perforated wall thereof is an imperforate wall tube 27, the opening in its lower end having a screen or sieve 28. The tube 27 is removably secured in position in the basket 23 by inserting the lower end thereof in a sleeve 29 (Fig. 3) fixed to the bottom wall of the basket within the axial opening thereof. The upper end of the tube 27 is flared and lies flush with the upper edge of the basket 23. The purpose of the tube 27 in the operation of the apparatus serves as a depository for dross or other foreign matter contained in the bath, which in the centrifuging action is attracted to the axis of the rotating parts by the vortex created and flows into the flared mouth of the tube and is retained at the bottom thereof by the sieve 28, any molten metal passing therethrough.

40 Surrounding the lower reduced portion of the receptacle 11 is an oven 30 provided with a plurality of nozzles 31 for projecting against the sides of the receptacle gas flames to maintain the tin and the objects to be coated at a sufficiently high temperature to facilitate the flow of the metal around the objects to thoroughly envelop them and in the centrifuging action the removal of all excess metal therefrom. Attached to the walls of the oven 30 and surrounding the enlarged portion 14 of the rotatable receptacle 11 is a housing or guard 32 provided at its upper end with a collar portion 33, the diameter of which is sufficiently large to receive the basket 23 when it is raised from the receptacle 11 during the centrifuging operation to be described shortly hereinafter. The portion 33 serves to prevent the scattering of molten metal particles into the space above the top of the guard 32 with the likelihood of injury to an operator as the rotating basket is raised from the receptacle 11. Substantially one-half of the portion 33 may be swung open about a hinge 34 to

70 permit the basket 23 to be moved from the apparatus to another position. To permit this the hydraulic cylinder (not shown) for operating the shaft 18 may be operatively mounted upon a pivotal arm (not shown) whereby the shaft 18 with the attached basket 23 may be swung to one side upon being drawn upwardly to the dotted line position, the basket detached therefrom, another basket attached thereto and then swung back 75 into axial alignment with the receptacle 11.

Upon the rotating basket 23 reaching the dotted line position thereof a circular brake surface 37 formed upon the upper end of the sleeve 19 engages a stationary friction 80 member 38 which may be supported in a suitable manner by a standard (not shown) fixed to the floor. The member 38 is ring shaped but cut open on one side to permit the shaft 18 with the basket 23 to be swung 85 to one side as described hereinbefore. Thus the basket 23 is quickly brought to a stop upon reaching its upper position.

90 In practicing the method of metal coating small objects with the hereinbefore described apparatus the bath of tin contained in the receptacle 11 is brought to a suitable temperature in the manner and for the purpose hereinbefore described. The bath of tin is then skimmed of any surface impurities and the basket 23 with the objects therein is lowered into the bath and when the basket has been completely submerged the receptacle 11 is caused to rotate. The speed of rotation of the receptacle 11 may be increased very rapidly by the normal acceleration of a motor or belt driving it through the worm 18. The bath of tin will accelerate more gradually, due to its friction on the walls of the receptacle 11. The ribs 26 95 of the receptacle 11 it will be apparent serve to facilitate the rotation of the bath of tin around the basket 23 and thus the latter is caused to rotate with it. In fact, the bath can not rotate much more rapidly than the basket, due to the surface friction created between the mass of tin, the basket and the mass of objects therein. As the velocity of the bath and basket increases the centre 100 of the bath collects the lighter or surface slag and impurities and the crater of the surface is finally lowered sufficiently to be intersected by the flaring top edge of the tube 27, thus segregating these impurities 105 so they cannot descend with the clean metal and be deposited on the objects in the basket. Just after this occurs, and not before, the level of the tin reaches the height of the objects in the basket 23, it is well to further cleanse the surface of the bath by sprinkling 110 it with a flux, such as rosin, tallow, any very high flash paint oil, or with dry zinc chloride or ammonium chloride. The specified fluxes are particularly adapted for use with 115 baths of tin and when other baths are em- 120 125 130

ployed suitable fluxes therefore should be selected. The impurities will be intercepted by the tube 27 and confined within that tube until the central level of the bath is lowered to a point just below the screen 28, where all but the finest of the slag and impurities will be deposited. The tube 27 as hereinbefore described is removable so that the slag and impurities may be readily removed therefrom and the screen 28 cleaned. The screen 28 is preferably cleaned at the end of each cycle of operation, just before fresh objects to be treated are put in the basket 23.

In the meanwhile, as the surface of the bath takes the well known form of a paraboloid of revolution of increasingly sharp curvature, indicated by the broken line 39, the tin overflows progressively past the knee or corner 40 of the receptacle 11, into the upper and outer enlarged portion 14 thereof. Obviously as this process continues the bath flows very gradually away from the basket and the therein contained objects, its surface moving through them both downwardly and outwardly, forming in the lower part of the receptacle 11 successively paraboloids of revolution. It will be noted that each drop of tin on any object near the surface of the bath is pulled in a direction normal to that surface by the resultant of centrifugal and gravitational forces. It will be noted that the surface-tension of this receding surface is also in this same direction. The method and apparatus of the present invention is particularly useful in that the last drop on any outward edge or corner of an object, which is very hard to throw off and which is likely either to remain or make a lump when cold or dry, or to fly off and spatter up others of the mass of objects is removed due to the additive stripping effect of gravity, centrifugal force and surface tension. Also since it is not necessary to remove the objects from the effects of the hot bath, additional heat is not required to keep the metal or material on their surface uniformly hot and free flowing and the formation of oxides and slags is thereby prevented.

It will be clear that, as soon as the bath has attained the speed of the receptacle 11, which can be determined in a number of ways, as by the power consumption going down, cessation of power loss in fluid friction, or by a simple observation through the top opening by a mirror, or more practically by noting once and for all the time it takes, there is no further advantage in continuing to revolve the basket 23, but rather a danger of cooling the parts and of sticking them together. The basket then should be raised to the position shown in dotted lines inside of guard ring 33, and its rotation should be stopped as quickly as possible, which may be accomplished through the

use of the brake surface 37 engaging the stationary friction member 38.

The power should be cut off from worm 13 and the receptacle 11 allowed to come to rest. The bath therein will also come to rest and become level, which is facilitated, it will be apparent, by the ribs 26 of the receptacle 11. It may require replenishing at this time.

The basket is removed from the spiders 21, dumped quickly so the objects will not stick together. The strainer 28 is cleaned, the basket is refilled, or another one already filled with objects ready for coating may be used, and replaced on the spider and then subjected to the molten bath which has been prepared in the manner previously described.

Although this invention has been disclosed and described in connection with the coating of small objects with tin, it will be understood that the invention is capable of other applications and is only to be limited by the scope of the appended claims.

What is claimed is:

1. A method of treating objects which consists in subjecting the objects to a treating material, and effecting a relative movement between the objects and the treating material while the objects are subjected to the material to remove excess material from the objects by the combined action of centrifugal force and surface tension.

2. A method of treating objects which consists in subjecting the objects to a treating material, and effecting a relative movement between the objects and the treating material while the objects are subjected to the material to remove excess material from the objects by the combined action of centrifugal and gravitational forces.

3. A method of treating objects which consists in subjecting the objects to a treating material, and effecting a relative movement between the treating material and the objects while the objects are being treated to cause the treating material to establish a hollow formation free of the objects.

4. A method of treating objects which consists in subjecting the objects to immersion in a treating material, and effecting a relative movement between the treating material and the objects while the objects are immersed to cause the treating material to establish a parabolic formation free of the objects.

5. A method of applying coating material to objects which consists in subjecting the objects to immersion in the coating material, and then centrifuging the residuary coating material free from the objects while maintaining the objects at their normal immersion level in the coating material.

6. A method of applying coating material to objects which consists in subjecting the objects to immersion in the coating material,

centrifuging the residuary coating material free from the objects, and then withdrawing the coated objects from their normal immersion level in the coating material.

5 7. A method of applying coating material to objects which consists in subjecting the objects to immersion in the coating material, centrifuging the residuary coating material free from the objects and causing a revolving of the latter about the axis of the material, and then withdrawing the coated objects from the normal immersion level of the material, the inertia of the objects causing them to continue to rotate whereby centrifugal force and surface tension removes any excess material therefrom.

8. A method of treating objects, which consists in subjecting the objects to immersion in a treating material, and effecting a 20 rotary movement of the material while the objects are subjected to the material in their normal immersion level therein to remove excess material from the objects by the combined action of centrifugal force and surface tension.

9. A method of treating objects, which consists in subjecting the objects to immersion in a treating material, and effecting a 30 rotary movement of the material and the objects while the objects are subjected to the material in their normal immersion level therein to remove excess material from the objects by the combined action of centrifugal force and surface tension.

35 In witness whereof, I hereunto subscribe my name this 9th day of November A. D., 1927.

ARTHUR HERMAN ADAMS.
